UNITED STATES PATENT OFFICE.

WILLIAM BOCK, OF RACINE, WISCONSIN.

GUIDE FOR MATCH PLATES.

Application filed June 20, 1921. Serial No. 479,025.

To all whom it may concern:

Be it known that I, WILLIAM BOCK, a citizen of the United States, residing at Racine, in the county of Racine and State 5 of Wisconsin, have invented certain new and useful Improvements in Guides for Match Plates, of which the following is a specification.

This invention relates to foundry appliances, and the primary object of the invention is to provide a novel guide for match plates of flasks, which is so constructed as to maintain a certain resistance on the match plate, during the raising and lowering there- 10 of on the flash pins, said resistance being formed by a pair of spring pressed tension guide bars, slidably mounted within the guide, the tension on the flask pins caused by the match plate, through the medium of the 15 spring pressed tension bars, eliminating the possibility of the pattern slipping, and the inconveniences caused by any unevenness in the surface of the flask pins, and any inconveniences caused by the cope portion of 20 the flask sticking.

Another object of the invention is to provide an improved guide for match plate of foundry flasks of the above character, which is durable and efficient in use, one that is 25 simple and easy to manufacture, one in which the sand or other foreign matter cannot reach the working parts thereof, and which can be readily and easily associated with the flasks at a minimum cost. 30

With these and other objects in view, the invention consists in the novel construction, arrangement and formation of parts, as will be hereinafter more specifically described, claimed and illustrated in the accompanying 35 drawings, forming a part of this specification, in which drawings:

Figure 1 is a fragmentary side elevation of a flask, showing the improved guide associated with the match plate thereof.

Figure 2 is a fragmentary end elevation of the flask showing the improved guide incorporated with the match plate thereof.

Figure 3 is a top plan view of the improved guide.

Figure 4 is a section taken on the line 4—4 of Figure 5.

Figure 5 is an end elevation of the improved guide.

Figure 6 is a longitudinal section through 55 the improved guide taken on the line 6—6 of Figure 3.

Figure 7 is a detail perspective view of one of the tension plates or bars.

Figure 8 is a detail perspective view of the other tension plate or bar. 60

Figure 9 is a transverse section taken on the line 9—9 of Figure 3.

Referring to the drawings in detail, wherein similar reference characters designate corresponding parts throughout the several 65 views, the letter A indicates a flask, which includes the cope 10 and the drag 11; B, the match plate interposed between the cope and drag; and C, the guide for the match plate.

The cope 10 and the drag 11, are provided 70 with the usual pins D and sockets F, which can be of the usual or any preferred construction.

As shown, the pins D are secured to the drag portion 11 of the flask A by means of 75 the face plate 12, and as shown, the pin extends upwardly from the face plate, and is substantially triangular shaped in cross section.

The socket F is attached to the cope portion 10 of the flask A by means of a suitable base plate 13, and this socket may be provided with an adjustable guide 14. This guide 80 is shaped to conform to the transverse configuration of the pin D.

As stated, the match plate B is interposed between the cope portion 10 and the drag portion 11 of the flask and extends outwardly of the ends thereof, and is suitably apertured for the reception of the 90 pins D.

The improved guides C are carried by the match plate B, and are adapted to slidably receive the pins D, and are formed, as will now be described, to exert a tension on the 95 pins.

As shown, the guides C for the match plate B includes a bottom plate 15 and a top plate 16. The bottom plate 15 is provided with outwardly extending apertured ears 17, 100 which are adapted to receive suitable fastening elements 18, by means of which the guides are secured in position on the match plates.

The bottom plate 15 is also provided with 105 a recessed portion 19, which opens out through one longitudinal edge of the plate. This recess 19 defines end walls 20, and a longitudinal wall 21. The end walls 20 are undercut as at 22, for a purpose, which will 110 be hereinafter more fully described. The top plate 16 overlies the bottom plate 15 and

is in facial abutment therewith, and is provided with a depending flange 23, on one of its longitudinal edges, which is adapted to fit the rabbeted portion 24 formed on the 5 longitudinal edge portion of the lower plate 15. This flange 23 closes the entrance portion of the recess 19.

The plates 15 and 16 have slidably mounted therebetween the relatively broad tension 10 plate or bar 26, and the relatively narrow tension bar or plate 27. These bars or plates 26 and 27 have their terminals bevelled as at 28, and inserted under the undercut portion 22 of the end walls 20. These plates are normally urged toward each other, by means of 15 springs 29 and 30. These springs have been shown of the leaf type, but it is to be understood that any suitable type of springs may be utilized for urging the plates toward 20 each other. It is preferred that the top and lower plates 15 and 16 be formed of brass, while the tension plates or bars 26 and 27 be formed of bronze or the like. The top wall or plate 16 is provided with a triangular 25 shaped cut out portion 31, which is braced along two of its sides, by means of an upstanding flange 32, which is adapted to engage the outer surface of the pins D as clearly shown in Figures 1 and 2 of the drawings. 30 The lower plate 15 is also provided with a triangular shaped opening 33, which is in direct alignment with the opening 31. The inner edge of the tension plate or bar 26 is provided with an inwardly extending V-shaped notch portion 34, which is adapted to engage the outer surface of the side walls of the pins D. The inner edge of the tension plate or bar 27 is provided with a V-shaped projection 35, which is adapted to 35 engage the inner surface of the side walls of the pins. The inner edge of the bar or tension plate 27 is provided with spacing lugs 36, which are adapted to engage the inner edge of the tension plate or bar 26. This 40 serves to hold the plates or bars 26 and 27 spaced a sufficient distance to permit the convenient insertion of the pins D into the guides.

In applying the improved guides to match 50 plates, it is merely necessary to aperture the match plate for receiving the pins D and to secure the guides in position. The guides and match plates are then slid into position on the pins D in the ordinary manner.

55 It can be seen that the tension plates or bars 26 and 27 will create a tension or resistance on the pins D, thus causing the steadyng of the flask, and absolutely preventing shifting of the pattern. The tension 60 plates also take care of any uneven spots on the flask pins, and facilitates the removal and eliminates the sticking of the cope portion of the flask.

From the foregoing description, it can 65 be seen that an improved attachment has

been provided for foundry flasks, of the above character, which will effectively guide the match plates to and from position, and which is so constructed that sand or other foreign matter cannot gain access thereto, 70 the guides being so constructed however, as to permit ready access thereto when it is desired to make repairs to the parts thereof.

Changes in details may be made without departing from the spirit or scope of this 75 invention; but,

I claim:

1. The combination with a flask including a cope portion, a drag portion, and a match plate interposed therebetween, a flask pin carried by one of said portions, a socket carried by the other portion for the flask pin, a casing carried by the match plate, oppositely disposed slidable tension plates carried by the casing for engaging the opposite sides of 85 the flask pin.

2. The combination with a foundry flask including a cope portion, a drag portion, and a match plate, sockets and pins carried respectively by the cope and drag portions, 90 guides secured to the match plate, tension plates slidably mounted in the guides arranged to engage the opposite sides of the flask pins, and spring means normally urging said tension plates into frictional contact with the opposite sides of the flask pins.

3. The combination with a foundry flask including a cope portion, a drag portion and a match plate interposed between said 100 portions, flask pins and sockets carried by said portions, guides carried by the match plate for engaging the flask pins including casings sliding tension plates carried by the 105 casings, and leaf springs arranged in said casings for normally urging the tension plates into engagement with the opposite sides of the flask pins.

4. The combination with a foundry flask including a cope portion, a drag portion, 110 and a match plate interposed therebetween, flask sockets and pins carried by the respective cope and drag portions, of a guide for the match plate including a two-part casing, the upper and lower parts of the casing having 115 openings formed therein to receive the flask pins, plates slidably mounted in the casing between the parts thereof shaped to conform to the configuration of the flask pins which they are to engage, and springs 120 engaging the walls of the casing and the outer edges of the tension plates for normally urging the tension plates into engagement with the opposite sides of the flask pins.

5. A guide for pins of foundry flasks comprising a casing including a top plate and a bottom plate, the bottom plate having a recess formed therein opening out through one edge thereof, the mentioned edge being 125 130

rabbeted, a depending flange formed on one edge of the top plate arranged to fit in the rabbeted portion, the opposite end walls of the bottom plate formed by the recess there-
5 in being undercut, said top and lower walls having recesses formed therein, shaped to conform to the configuration of the flask pins with which they are to be used, said openings being formed relatively larger
10 than the flask pins, a relatively wide tension plate arranged in the casing, a relatively narrow tension plate mounted in the casing, the ends of the tension plates be-

ing bevelled and fitted in the undercut portions of said end walls, the inner edge of 15 one of said tension plates having a notched portion formed therein to conform to the configuration of the flask pin with which the guide is to be associated, the other tension plate having a projection formed thereon 20 arranged to conform to the configuration of the flask pin, and leaf springs arranged in the casing and engaging the opposite sides of the tension plates to normally urge the same into engagement with the flask pins.

WILLIAM BOCK.
